TAPE CARTRIDGE CARRIER

Richard D. Dilyard, Wooster, Ohio, assignor to Rubber-maid Incorporated, Wooster, Ohio, a corporation of Ohio

Filed Feb. 5, 1968, Ser. No. 10,429

Term of patent 14 years

(Cl. D87—1)

FIG. 1

FIG. 2

FIG. 3

FIG. 4

FIG. 5

FIG. 6

FIG. 1 is a top plan view of a tape cartridge carrier embodying my new design.

FIG. 2 is a side elevational view thereof, the opposite side being a mirror image of the side shown.

FIG. 3 is an elevational view of the right end of FIG. 1.

FIG. 4 is a cross sectional view taken lengthwise through the middle of FIG. 1.

FIG. 5 is a bottom plan view thereof.

FIG. 6 is an elevational view of the left end of FIG. 1.

I claim:

The ornamental design for a tape cartridge carrier, as shown and described.
